Dean W. Myers, Newport Beach, Calif., assignor to
Jaybee Manufacturing Corp., Los Angeles, Calif., a
corporation of California

Filed May 20, 1963, Ser. No. 74,966

Term of patent 14 years

(Cl. D10—8)

FIG. 1.

FIG. 2.

FIG. 3.

FIG. 4.

FIG. 5.

FIG. 6.

FIGURE 1 is a front elevational view of a cabinet pull or similar article incorporating my invention;

FIG. 2 is a side elevational view thereof;

FIG. 3 is an end elevational view thereof;

FIG. 4 is an enlarged fragmentary sectional view taken along a plane corresponding to line 4—4 of FIG. 1;

FIG. 5 is an enlarged sectional view taken along a plane corresponding to line 5—5 of FIG. 1; and

FIG. 6 is a front elevational view of a modified form of the cabinet pull shown in FIG. 1, differing therefrom in the reversal of the contrasting areas.

The characteristic feature of my design for a cabinet pull or similar article resides in the configuration and arrangement of the specific decorative details indented on

the front surface thereof. The stippled shading indicates contrasting areas.

I claim:

The ornamental design for a cabinet pull or similar article, substantially as shown and described.
